UNITED STATES PATENT OFFICE.

FRANK KILTS AND LOUIS A. PARADIS, OF CHICAGO, ILLINOIS.

OXYACETYLENE CUTTING-MACHINE FOR CIRCULAR PLATES.

1,348,363.

Specification of Letters Patent. Patented Aug. 3, 1920.

Application filed May 5, 1919. Serial No. 294,889.

To all whom it may concern:

Be it known that we, FRANK KILTS and LOUIS A. PARADIS, citizens of the United States, residing at Chicago, in the county of Cook and State of Illinois, have invented certain new and useful Improvements in Oxyacetylene Cutting-Machines for Circular Plates, of which the following is a specification.

10 Our invention relates to an oxyacetylene machine for cutting circular plates, and has particular reference to a hand operated portable machine which can easily and quickly be moved from place to place and set in proper position.

Another object of our invention is the provision of a machine which can be easily and quickly adjusted for the cutting of plates of various diameters, and which will 20 cut the plates accurately, and which is simple and efficient in operation and easily handled.

Another and further object of our invention is the provision of a machine which can easily be adjusted to cut beveled edges or 25 straight edges on the plates to conform to different requirements and without any material alteration of the machine.

Our invention will be further and better understood by reference to the accompanying 30 drawings in which—

Figure 1 is a view in elevation of our improved machine.

Fig. 2 is a plan view looking downward upon the machine, and,

35 Fig. 3 is a view of a bracket which is to be attached to the machine for cutting small plates.

Referring now specifically to the drawing, a circular base plate 10 is shown which 40 has a plurality of sharpened pins 11, 11, extending downwardly therethrough, these pins being sharpened on their lower ends to prevent the base plate from slipping out of position. A member or standard 12 having 45 an annular shoulder 13 near its lower end is mounted upon and extends through the base plate 10, the shoulder 13 serving as a bearing surface between the member 12 and the base plate 10, with a nut 13^a in threaded engagement with the lower end of the member 50 12 to hold the said member securely to the base plate 10. Mounted upon the upper end of the member 12 is a bifurcated D-shaped member 14, comprising an upper portion 14^a

and a lower portion 14^b which rests upon an 55 annular collar 15 formed upon the member 12 near its upper end and having an integrally formed upwardly extending portion 29 for the purpose hereinafter described. Mounted upon the upper end of the member 60 12 and between the portions 14^a and 14^b of the member 14 is a gear wheel 16 which is keyed to the member 12 or secured thereto in any suitable manner, so that as the gear wheel 16 is rotated the member 12 will be 65 rotated also, and in a corresponding direction. Mounted in the outer end of the member 14 is a shaft 17 having a worm gear 18 mounted thereon and in mesh with the gear wheel 16. A collar 19 is secured to the shaft 70 17 by means of a key 20, which holds the shaft in proper position. A brace rod 23 is secured to the portion 29 of the member 14 at its inner end, a head portion 24 being provided within which the portion 29 is 75 mounted. The brace rod 23 at its outer end is secured to the upper end of a stand 30 by means of a bolt 25 and which acts as a support for the outer end of the shaft 17 and holds it in proper position, the lower ends of 80 the stand 30 resting upon the ground. The shaft 17 extends through the outer end of the member 23 and is held against outward movement by a collar 26 which is secured to the shaft 17 by means of a pin 27, the collars 85 19 and 27 which abut against the outer end of the member 23 and the member 14 respectively therefore serve to hold the shaft 17 in proper position. A crank 28 is secured to the outer end of the shaft 17 so that an operator 90 may turn the shaft 17 as desired.

Secured to the member 21 is an outwardly extending arm 31 which is clamped to the member 12 by means of a pair of bolts 32, 32, and which is movable up and down upon 95 the member 12 so as to provide proper adjustment of the blow torch as hereinafter described. Secured to the outer end of the arm 31 is a U-shaped torch holder 32^a, having a member 33 mounted thereon, to which is secured a set screw 34 in threaded engagement with the member 32 on one of its sides, and which is adapted to be moved by means of the screw 34 so as to hold the blow torch in position shown in Fig. 2. Holes such as 35, 35 are provided in the member 31 so as to enable the U shaped member 32 to be positioned at different points on the member 31

by means of the bolt 36 on the under side of the member 32. Extending outwardly from the member 12 and integral therewith is an arm 37 to which is secured, by means of a pair of bolts 38, a lengthening arm 39 having a hollow head portion 40 formed integrally therewith and within which is fitted a shoe 41 which has a projection 42 on its rear side which fits into the socket portion 40 of the member 39, and which allows for a tilting of the member 41 for the purposes hereinafter described.

The member 41 has a vertical groove 43 within which is mounted a nozzle holder 44 having a hole 45 in its outer end through which a nozzle 46 of the torch extends. Secured to the nozzle holder 44 is an adjusting screw 47 in threaded engagement with the upper end of the member 41 and adapted to move the nozzle holder 44 up and down in the slot 43 so as to provide a proper adjustment of the nozzle away from the plate which is being cut. The blow torch comprises the nozzle 46, which fits through the nozzle holder 44 and is connected to a pair of members 48 and 49 which are secured in turn to a cylindrical member 50 which is adapted to be held in the holder 32. Suitable pipes 51 and 52 lead to the nozzle 46 and have connected thereto in any suitable manner a pair of hose pipes 53, 54 which lead to supply tanks of oxygen and acetylene, or any other suitable gas for use in the blow torch.

Referring now specifically to Fig. 3, and wherein is shown a bracket 55 such as may be used for cutting small diameter plates. This bracket has a pair of holes 56, 56, by means of which the bracket is secured to the member 37 by means of bolts 38. A hole 57 is provided by means of which the lengthening arm 39, herein previously described, is attached to the bracket 55. In case it is desired to cut plates with beveled edges, then the members 41 and 44 can be tilted at the proper angle and the cutting torch securely fastened in position as hereinafter described.

It will also be understood that different length extension arms may be secured to the members 31 and 37, thus making it possible to cut plates of different diameters than what is shown by the adjustments of the machine as shown in the drawings. It will be thus understood that the diameter of the plates is limited only by the length of the shaft 17 and the brace 23.

The method of operation of the machine is extremely simple. The metal squares or plates from which the circular plates are to be cut are marked in any suitable manner from a suitable center so that the machine may be positioned properly and the torch adjusted in its proper position with respect to the angle of cut and distance of the metal by means of the screw 47 and the shoe 43

which fits into the head portion 40 of the member 39. The base 10 is properly adjusted, the blow torch is lighted, and an operator turns the crank 28, thus moving the member 12 which carries with it the arms 31 and 37, carrying the torch around in a circle as fast as may be desired in order to enable the frame to cut through the metal out of which the plates are being cut. This will, of course, depend upon the quality of the metal, its hardness, thickness, etc. Upon a plate being cut the machine is sufficiently light so that it may be picked up and moved to a new position and where the operation is continued.

While we have described more or less precisely the details of construction, we do not wish to be understood as limiting ourselves thereto, as we contemplate changes in form and the proportion of parts, and the substitution of equivalents, as circumstances may suggest or render expedient, without departing from the spirit or scope of our invention.

We claim:

1. In a plate cutting device the combination of a base, a rotatable standard mounted upon said base, a gear wheel mounted upon said standard, hand operated means for turning the said gear wheel, and a pair of arms secured to said standard for holding a blow torch in position.

2. In a plate cutting device, the combination of a base, a rotatable standard mounted upon said base, a gear wheel mounted upon said standard at its upper end, hand operated means for turning the gear wheel, a pair of arms secured to said cylindrical member for holding a blow torch in position, one of said arms being adjustable vertically on said rotative member and an adjustable nozzle holder secured to the other one of said arms.

3. In a plate cutting device, the combination of a base, a rotatable standard mounted upon said base, a gear wheel mounted upon said standard at its upper end, a shaft having a gear wheel mounted thereon and in engagement with said first mentioned gear wheel, means for supporting the said shaft in co-operative position, an adjustable arm secured to said standard for supporting a blow torch, and means secured to said standard for holding a gas supply hose in position.

4. In a plate cutting device, the combination of a base, a rotatable standard mounted upon said base, a gear wheel secured to said standard at its upper end, a shaft having a gear wheel mounted thereon and in mesh with said first mentioned gear wheel, a plurality of arms for supporting a blow torch in position, one of said arms being adjustable vertically on said standard, and a holder secured to one of said arms, the said holder

being capable of adjustment to various angles.

5. In a plate cutting device, the combination of a base, a rotatable standard mounted upon said base, a plurality of laterally extending arms secured to said rotatable standard adapted to hold a blow torch in posi-

tion, a hand operated means for turning said arms around said base.

Signed at Chicago, Illinois, this 30th day ¹⁹ of April, 1919.

FRANK KILTS.
LOUIS A. PARADIS.
